ABSTRACT OF THE DISCLOSURE

Gravel filter pipes are made by placing an inflatable body within a perforated support body and then inflating it so that it bears against the perforated body; gravel and bonding agent are then poured around the outside of the body, the bonding agent sets, and the inflatable body is deflated.

Field of the invention

The present invention relates to a method for making gravel filter pipes.

Description of the prior art

Gravel filter pipes comprise a supporting internal tubular body provided with openings such as holes or slits and a layer of bonded gravel situated externally thereon. These pipes are made by placing an outer form around the tubular supporting body, pouring an aqueous mixture of gravel and bonding agent into the gap between form and body, then vibrating the mixture and finally allowing the mixture to set.

It is necessary in this manufacture to close temporarily the openings in the internal tubular body, so that the unset gravel mixture does not leak through them. Closure of these openings has heretofore been beset with difficulties. Most often sheet metal has been employed in the prior art for this purpose. The sheet metal is cylindrically curved and put into the interior of the supporting body. The sheets are braced, for example by wedges. In spite of carefully bracing of the sheets, it happens again and again that some individual wedges loosen when the mixture consisting of gravel and a bonding agent is vibrated. The mixture leaks through the openings in the supporting body into the pipe interior. In the case of long pipes with a comparatively big diameter this happens also owing to the fact that the sheets bend towards the interior and, therefore, at some points do not lie close to the openings. As a result, during the manufacturing process the sheet metal often sticks to the supporting body and can only be taken out with difficulty, in which case the sheets sometimes are so damaged that they are either entirely unfit for further use or can only be made reusable by toilsome manual labor.

Objects of the invention

In view of the above difficulties, objects of the present invention are to provide a method for manufacturing gravel filter pipes wherein:

the openings of an inner tubular body are sealed during pouring and setting of a gravel and bonding agent mixture;
the sealing of an inner tubular body is unaffected by vibration of a poured mixture;
the seal is easily placed into the tubular body before pouring; . . .

2

the seal is easily removed following setting of the mixture;
the seal is not damaged during use and can be reused.

Other objects and many of the attendant advantages of this invention will be readily appreciated as the same becomes better understood by reference to the following detailed description when considered in connection with the accompanying drawing in which like reference numerals designate like parts thereof:

Description of the drawing

The only figure of the drawing is a partly sectioned view of a filter pipe being manufactured according to the method of the invention.

Summary of the invention

In order to attain the objects of the invention, the method of the invention involves putting an elastic, hollow, inflatable body into the interior of a perforated, tubular supporting body and inflating it therein. Because the interior limits of the gravel filter pipe are formed by the supporting body, a comparatively thin-walled hollow body is sufficient for sealing the openings of the supporting body. Such a hollow body, therefore, is very light and does not require much elastic material.

Because the hollow body to be used according to the invention need not be relatively thick and dimensionally stable, it adapts during inflation completely to all existing local unevenesses of the supporting body and reliably seals its openings, even if the inner surface of the supporting body is not entirely cylindrical.

According to the invention, a rubber, inflatable hollow body, made for example of latex and having a diameter corresponding to that of the perforated support body to be used for the pipe, is let into the interior of the support body. Then, the hollow body is inflated via a valve until it bears tightly against the inside of the support body and seals its openings. Then a mixture of gravel and bonding agent is poured into the hollow space between the support body and an outer form. The mixture is next vibrated to assure its uniform placement. After the mixture has set, the inflating air is allowed to escape from the hollow body, whereupon the hollow body is withdrawn without difficulty and is ready for reuse.

The inflatable hollow body must be inflated to a pressure that will at least be greater than the static pressure of the gravel and bonding agent mixture surrounding the support body. It is also, of course, necessary that the pressure in the hollow body be sufficient to withstand the dynamic pressures arising from any vibrations used to obtain uniform placement of the mixture.

Description of the preferred embodiments

The figure shows outer cylindrical forms 1 having vertical reinforcing elements 5. These forms 1 are held, in this example by their weight, to annular angle support rings 2 which are part of the tubular support bodies 6. The tubular support bodies have openings 3 in the form of slits or holes.

An inflated hollow body 4 is shown within the tubular support bodies. The hollow body is made of two sections and lapped at 7. Inflation of the hollow body is via an air valve 8.

A mixture of gravel and bonding agent is fed around the support body through the gaps 9.

I claim:

1. A method for placing a bonded gravel layer on a perforated support body to make gravel filter pipes, comprising, in sequence, the steps of: placing an inflatable body within a perforated support body and placing a form around the outside of the support body; inflating the inflatable body to bring it to bear with a predetermined pressure on the perforated internal surfaces of the support body; pouring a mixture of gravel and bonding agent around the outside of the support body; allowing the 10 gravel and bonding agent mixture to set; and deflating the inflatable body.

2. A method as claimed in claim 1, further comprising the step of vibrating the mixture of gravel and bonding agent after the step of pouring before the step of setting. 15

3. A method as claimed in claim 1, further comprising

the step of removing the form from around the outside of the support body after the mixture has set.

4. A method as claimed in claim 1, further comprising the step of removing the inflatable body from within the 5 perforated support body, after the step of deflating.
